UNITED STATES PATENT OFFICE.

JOSEPHINE RUSSELL, OF TABOR, IOWA.

DESIGN FOR A BADGE.

SPECIFICATION forming part of Design No. 33,015, dated July 31, 1900.

Application filed June 13, 1900. Serial No. 20,212. Term of patent 7 years.

To all whom it may concern:

Be it known that I, JOSEPHINE RUSSELL, a citizen of the United States, residing at Tabor, in the county of Fremont and State of Iowa, 5 have invented and produced a new and original Design for Badges, of which the following is a full, clear, and exact description, reference being had to the accompanying drawings, forming a part hereof.

10 Figure 1 is a front elevation of my design, and Fig. 2 is a vertical section on line 2 2 of Fig. 1.

15 As shown in the drawings, the design consists of a blade or body portion 1 of substantially-uniform thickness, having lower sharp corners and upper rounded corners, the upper edge of the blade forming a reentrant angle 2, from the base of which extends a tapering ridge 3, which curves rearwardly as it

leaves the blade and is thence continued downward in the form of a tapering pin 4. On either side of the ridge 3 are formed oblong or oval panels 5, raised beyond the plane of the outer face of the blade, the latter being provided within the panels with a pocket 6, 25 depressed below the plane of the outer face of the blade, said pocket being adapted to receive a plate or disk bearing a portrait 7.

Having described my invention, what I claim is—

20 The design for a badge, as herein shown and described.

In testimony whereof I affix my signature in presence of two witnesses.

JOSEPHINE RUSSELL.
